Inventor:

Irene Miller.

UNITED STATES PATENT OFFICE.

IRENE MILLER, OF CORTLANDVILLE, NEW YORK.

IMPROVEMENT IN STOVE-PLATFORMS.

Specification forming part of Letters Patent No. 122,631, dated January 9, 1872.

I, IRENE MILLER, of the town of Cortlandville, in the county of Cortland and State of New York, have invented certain Improvements in Platforms for Stoves, of which the following is a specification:

Figure 1 is a perspective view of the platform. Fig. 2 is a section of the leg through the wheel.

a is a frame, of wood or iron, and made to conform in shape and size to the bottom plate of the stove. *b b* are the legs to this frame, which may be permanently attached to the frame or held by lugs upon the under side of the frame in the ordinary way that stove-legs are held to the bottom of the stove. The leg *b* is made with a socket, *c*, Fig. 2, into which fits loosely the spindle *d*, in the lower part of which is the wheel *f*, it being the ordinary form of the caster. *C* is a set-screw passing through

the leg to the spindle *d*, and calculated to hold the spindle and wheel in the position desired.

The object of the invention is to practically make the stove movable at will, and, when moved to the desired position, by setting the casters in the right position or direction and tightening the set-screws, render the same immovable, and of course make the stove stationary as if upon the ordinary leg.

I claim—

The combination of the stove-stand or platform *a*, caster *b e d*, and set-screw *C*, substantially as and for the purpose hereinbefore set forth.

IRENE MILLER.
